UNITED STATES PATENT OFFICE.

PAUL KUHNE, OF BIRMINGHAM, ALABAMA.

CONCRETE FLOOR CONSTRUCTION.

1,329,978.

Specification of Letters Patent.

Patented Feb. 3, 1920.

Application filed January 23, 1919. Serial No. 273,528.

To all whom it may concern:

Be it known that I, PAUL KUHNE, a citizen of the United States, residing at 2300 Orange avenue S., Birmingham, in the county of Jefferson and State of Alabama, have invented certain new and useful Improvements in Concrete Floor Constructions, of which the following is a specification.

This invention relates to an improvement 10 in concrete floor construction where hollow spaces are formed between the beams, the invention being more particularly directed to the steel forms about which the concrete is poured to provide such hollow spaces.

15 As heretofore constructed, the forms have been so formed as to require the application of the usual metal lathing to close the space provided by the forms and to provide for the application of the ceiling, thus requiring the additional material of such lathing and the time and labor in applying same.

20 The present improvement is directed to combining the lathing with and as a part of the form, and so constructing the combined form that the concrete, when poured, will fill between projections of such lathing, and thus, when the centering is removed, leave a completely inclosed space, and a comparatively smooth surface for the application 25 of the ceiling.

Another object is the construction of the 30 form that it will be completely reinforced, and the utilization of certain of the reinforcing means as a support for the usual metal bars to be embedded in and reinforce 35 the concrete beams formed between the forms.

The invention in the preferred form is 40 shown in the accompanying drawings, in which:—

Figure 1 is a sectional view of a portion of a floor, with the improved forms in place.

Fig. 2 is a plan, partly broken out, of the same.

45 Fig. 3 is a side elevation of the form.

Fig. 4 is an enlarged detail, showing the form of the lathing bottom of the form.

Fig. 5 is a section of the same on line 5—5 of Fig. 4.

50 Fig. 6 is a section on the line 6—6 of Fig. 4.

The present invention is particularly concerned with the forms, which as understood are to be arranged on a centering or support, in spaced order, and the concrete 55 poured over and around the same. The

forms thus provide open spaces between spaced concrete beams in the completed floor structure.

The improved form is made of steel, or the like, having a cross sectional dimension required, and is to be given any desired shape. As shown, the strip forming the structure is bent in a form having a straight bottom 1, comparatively straight side walls 60 2, and a rounded top portion 3. The strip is formed over forming and staying bars or rods 4, shaped to correspond with the shape of the sides and top, and preferably tied to the strip, as at 5. Any desired number of 65 such bars 4 may be used, in order to secure the desired rigidity of the form.

The bottom of the form is constructed to resemble the usual metal lathing, and this constitutes one of the important features of 70 the present invention. For this purpose the bottom of the form is provided at regular intervals with suitable incisions, dividing the material so that the same may be bent downwardly from the bottom as spurs 6, 80 and walls 7. The formation is such that the spurs are of greater length than the side walls, as clearly seen in Fig. 5, so that the spurs may rest upon the centering and support the bottom of the form above the same. 85 The concrete when poured will thus flow around the spurs and into the openings and between the walls 7. A layer of concrete is thus provided, which is interlocked with the bottom of the form, which closes the 90 space of the form, and which provides a surface on which the finished ceiling may be readily applied.

The side walls of the form are preferably 95 corrugated, as at 8, or may be strengthened to preserve their rigidity in any other desired manner. The side edges of the strip forming the form, are preferably extended upwardly from the central line of the top, as at 9, and the ends interlocked at 10. 100 Rivets or other fastenings 11, secure the upwardly-projecting meeting portions. A T-head is thus formed which when embedded in the concrete, absolutely prevents the sagging of the form.

105 The respective forms are arranged in spaced relation, so that the concrete may fill the space between such forms to provide the necessary floor beams. The present invention contemplates the use of interbracing 110 and fastening means for the adjacent forms, in inverted U-bars 12 and 13, arranged as

upper and lower spacers, with the sides of the forms provided with loops 14, to receive the side bars of such spacers. The lower spacers 14 are so arranged with relation 5 to the ceiling line of the contemplated structure, that such spacers will serve as supports for the floor bearing reinforcing rods 15, usually embedded in the concrete beams, and which of course are applied to pouring the 10 cement.

The use of the improved form will obviate the difficulty of applying the usual metal lathing for ceiling purposes, and the form 15 itself provides a more rigid structure and one having advantages over forms heretofore used for this purpose.

Having thus described the invention, what is claimed as new is:—

1. A sheet metal form for concrete floor 20 construction having a bottom cut to form openings, the material of the bottom within the plane of the opening being in part bent downwardly to form wall portions extending below and at an angle to the plane of 25 the bottom and in part bent downwardly to form spurs extending below the bottom and below the lower edges of the wall portions.

2. A sheet metal form for concrete floor 30 constructions having a bottom slitted to leave side and end portions divided from each other and connected with the bottom, said side portions being bent downwardly

from and at an angle to the bottom and the end portion being bent downwardly below 35 the bottom, the bending of the side and end portions forming an opening in the bottom within the plane of the bent portions.

3. A form for concrete floor construction comprising a sheet metal hollow body having a bottom, substantially parallel side walls, a rounded top, the meeting edges of such rounded top being interlocked above the top to form a rib, and stay bars within and bearing against the sides and top of the 45 body, the terminals of such bars resting on the bottom, said bottom being formed with openings having side walls projecting below the plane of the bottom and end walls, forming spurs projecting below the plane of the 50 bottom and below the lower edges of the side walls.

4. A form for concrete floor constructions comprising a sheet metal hollow body having a bottom, substantially parallel side 55 walls, and a rounded top, the meeting edges of the sheet forming the body being projected above the rounded top and longitudinally thereof as a rib, and stay bars within and bearing against the body, the terminals 60 of said bars resting on the bottom of the body and the intermediate portions of such bars bridging the meeting edges of the body forming strip.

In testimony whereof I affix my signature. 65
PAUL KUHNE.
